UNITED STATES PATENT OFFICE

2,600,533

MEMORANDUM PAD UNIT

Carl C. Harris, Orange, Mass., assignor to The
Stencil Co., Orange, Mass., a corporation of
Massachusetts

Application July 26, 1950, Serial No. 175,959

3 Claims. (Cl. 281—15)

1

This invention relates to improvements in memorandum pads, and the object thereof is to provide a novel desk pad or memorandum pad appliance with novel means for clamping the sheets of the pad in place and in which the appliance is provided with means for detachably supporting a pencil, or other marking implement, so that it can be conveniently removed for use and readily replaced upon completion of its use.

Usual types of such appliances for holding a stack of removable sheets of writing paper contain no means for retaining a marking implement, such as a pencil or pen, when not in use. As a consequence the marking implement is often misplaced or lost so that when the user desires to make a memorandum, such, for example, as during a telephone conversation, he is greatly inconvenienced by the loss or misplacement of the marking implement.

One of the objects of the invention, therefore, is to provide a memorandum pad appliance with such convenient means upon it for replaceably holding a marking implement so as to insure its presence when needed.

Usual marking implements, such as pencils or pens, are provided with a resilient clip for holding them in the pocket of the user. A further object of the invention is to provide the memorandum pad appliance with means by which the marking implement can be detachably secured to the pad in parallelism with and spaced from the uppermost sheet of the pad, so that the point of the implement will not be liable to be damaged and which will also enable the marking implement to be conveniently removed and replaced with a minimum effort upon the part of the user.

More specifically the object of the invention is to provide such a construction in which the pad of sheets is clamped to the base of the appliance by a narrow, thin, flat clamping plate having an upwardly offset central portion to receive the clip and position the marking implement lengthwise of, in parallelism with, and above the sheets of the pad.

A further object of the invention is to provide a construction of the clamping plate in which the offset central portion presents parallel guides extending transversely of the plate acting to position the marking implement.

A further object of the invention is to provide a construction in which at least one of the ends of the clamping plate presents a downwardly offset channel-shaped section forming a support for an additional marking implement provided with a clip.

These and other features and objects of the

2

invention will appear more fully from the accompanying description and drawing and will be particularly pointed out in the claims.

This application is a division and continuation in part of application Serial Number 589,948 filed April 24, 1945, now abandoned, and also of application Serial Number 739,603 filed April 5, 1947, now Patent No. 2,527,216 granted October 24, 1950.

10 The drawings illustrate preferred embodiments of the invention; in which,

Fig. 1 is a view in perspective of one embodiment;

Fig. 2 is a view, somewhat enlarged and taken 15 chiefly in cross section, of the construction shown in Fig. 1;

Fig. 3 is a view in perspective of a second embodiment; and,

Fig. 4 is a view in perspective of a third embodiment of the invention.

The memorandum pad appliance of this invention comprises a flat base, preferably of rectangular shape and of metal or other suitable material. This base may rest directly upon

25 the desk or other support, or it may be provided with any suitable form of legs or supporting structure. The base supports a stack of uniform rectangular sheets of paper, either separate or secured together at one edge in the usual manner.

30 The marking implement, as pointed out, may be either a pen, pencil, or other suitable device, and for convenience the term "pencil" has been used herein as including any such marking implement.

In the construction illustrated in Figs. 1 and 2 the base 1 is of rigid sheet material, such as metal, plastic, or the like, and is provided at each end with reversely bent arcuate extensions

40 having terminal portions 2 and 3 spaced from and underlying the base and extending toward each other and provided with resilient antifriction members, shown in the form of resilient studs 4, adapted frictionally to engage the surface of the desk or other support. Preferably as illustrated the terminal 3 is spaced a greater distance than the terminal 2 from the base so that the appliance will stand in a conveniently inclined position.

45 The pad 5 of sheets of paper is firmly clamped to the base by a narrow, thin, flat clamping plate 6 of suitable rigid material, such as metal, which overlies the face of the end portion of the uppermost sheet, and adjustable means are provided for securing this clamping plate adjacent its ends to the base. In this construction suitably spaced posts 7 extend vertically upward from the base

50

and pass through apertures adjacent the ends of the clamping plate and nuts 8 threaded to the posts engage the upper face of the clamping plate and thus firmly secure the stack of sheets in place on the base. The posts in this construction pass through holes formed for the purpose in the stack of sheets.

The pencil 9 illustrated is of the thin, flat type having the lead 10 adjustable therein and projecting from the point thereof and the eraser 11 mounted in the opposite end. The pencil is provided with a suitable clip 12 herein shown as of the type illustrated in Patent No. 2,414,810 granted January 28, 1947.

The clamping plate 6 is provided with an offset central portion 13 extending well above the top of the sheets of paper so that the pencil may be held in place resting upon this offset portion 13 with the free end of the clip underlying this offset portion and holding the pencil firmly in place. In this position the pencil will be held firmly supported in spaced parallelism with the uppermost sheet of the stack and extending longitudinally thereof.

Thus it will be seen that the pencil may readily be removed from and replaced in position, will not be likely to be lost or mislaid, and will always be available for instant use.

The embodiment of the invention illustrated in Fig. 3 is in its main features similar to that described. It comprises a suitable flat rectangular base 21 with the stack of sheets 22 resting thereupon. The clamping plate 23 is also a narrow, thin, flat plate of metal, or other rigid material. The base is similarly provided with vertically upstanding posts near each edge which pass through suitable apertures in the stack of sheets and have threaded thereto the nuts 24 so that the clamping plate firmly clamps the stack of sheets to the base. In this case, however, the apertures in the clamping plate through which the posts pass are of the bayonet type with the larger portions 25 of a size to enable the nuts 24 to pass through and thus enable the clamping plate to be removed and replaced without entirely disengaging the nuts from the posts.

The clamping plate is provided with the upwardly offset central portion 26 to receive the clip 27 of the pencil 28 therebeneath and thus to support the pencil in spaced parallelism with the uppermost sheet of the stack.

A further feature of the invention is embodied in this construction in that the clamping plate at each side of this offset central portion presents parallel guides extending transversely of the clamping plate and which act further to position the pencil and insure its standing in central longitudinal position. These parallel guides are shown as formed by upwardly extending bent portions 29 on the clamping plate connecting the offset portion 26 to the main body of the clamping plate.

A further feature of the invention is illustrated in this form in that the clamping plate is formed at each end to present a downwardly offset channel-shaped section to form a support for an additional pencil provided with a clip. At one end this channel-shaped section presents a flat bottom portion 30 so that a flat pencil of the type illustrated may be mounted thereon with its clip extending therebeneath, while at the other end this channel-shaped section is of a semi-cylindrical form 31 adapted to hold a cylindrical pencil with the clip extending therebeneath.

A further embodiment of the invention is illus-

trated in Fig. 4, in which the base 41 is of similar form to that shown in Figs. 1 and 2, and provided with similar extensions at each end having the terminal portions 42 and 43 provided with the studs 44.

The stack of sheets 45 is similarly held clamped to the base by the narrow, thin, flat clamping plate 46. But in this case the posts 47 extending upward from the base and provided with the nuts 48 threaded thereon pass entirely outside of the stack of sheets 45 so that it is not necessary to form apertures through the stack of sheets. Furthermore, the ends 49 of the clamping plate extend down against and past each side edge of the base, and thus act in positioning the clamping plate and giving a finished appearance.

The pencil 50 is shown as of the same type illustrated in the other figures and provided with a similar clip 51 and the clamping plate is of the same construction as that illustrated in Fig. 3 having the upwardly offset central portion 52 with the pencil resting on the top thereof and the clip passing therebeneath. Also the clamping plate is provided with the same parallel guides 53 formed therein extending in parallelism transversely of the plate and acting to position the pencil.

Having thus described the invention, what is claimed as new and desired to be secured by Letters Patent, is:

1. A memorandum pad construction having means for securing a stack of uniform rectangular sheets to a base comprising a narrow thin flat clamping plate of rigid material overlying the face of the end portion of the uppermost sheet, adjustable means for securing the clamping plate adjacent its ends to the base, said clamping plate having an upwardly offset central portion adapted to receive a pencil clip therebeneath and thereby to support the pencil at right angles to the clamping plate and in spaced parallelism with, and longitudinally of, the uppermost sheet of the stack.

2. A memorandum pad construction as defined in claim 1, in which at least one of the ends of the clamping plate presents a downwardly offset channel-shaped section forming a support for an additional pencil provided with a clip.

3. A memorandum pad construction as defined in claim 1, in which the clamping plate at each side of the said offset central portion presents parallel guides extending transversely of the plate acting to position the pencil.

CARL C. HARRIS.
